HEN'S NEST

Lorraine B. Thomas, Pueblo, Colo.

Application September 9, 1949, Serial No. 4,916

Term of patent 7 years

(Cl. D12—2)

To all whom it may concern:

Be it known that I, Lorraine B. Thomas, a citizen of the United States, residing at Pueblo, in the county of Pueblo and State of Colorado, have invented a new, original and ornamental Design for a Hen's Nest, of which the following is a specification, reference being had to the accompanying drawing, forming part thereof.

I claim:

The ornamental design for a hen's nest, as shown.

LORRAINE B. THOMAS.
